UNITED STATES PATENT OFFICE

1,996,633

FIRE EXTINGUISHING APPARATUS.

Emil Tyden, Hastings, Mich.

Original application June 30, 1930, Serial No. 464,940. Divided and this application July 28, 1933, Serial No. 682,556

5 Claims. (Cl. 137—161)

This application is a division of my co-pending application Serial No. 464,940, filed June 30, 1930, Patent No. 1,947,890, issued February 20, 1934.

5. The purpose of this invention is to provide in a fire extinguishing sprinkler system the means of venting the air pressure by which the main valve which controls access of water to the system is held seated, independently of the opening of the 10 discharge heads, so that the pipe system shall be occupied with water approximately to the discharge heads when the latter are opened by heat due to fire in the apartment; and so that instead of the discharge from the heads immediately following their opening being a blast of air fanning the fire, the discharge of the water, and this without the delay which occurs when the opening of the 15 sprinkler heads by heat is relied upon for fanning the pressure and causing the water controlling valve to open.

This divisional application is directed to specific construction of the valve device which controls the release or venting of the air pressure for adapting it to be operated for such release by a 20 temperature-responsive device, and to certain specific construction of said temperature-responsive device.

The invention consists in the elements and features of construction shown and described as indicated in the claims.

30. In the drawings:

Figure 1 is a diagrammatic view showing a part of a fire extinguishing installation in connection with which valve devices embodying the 35 invention of this divisional application are employed.

Figure 2 is a sectional side elevation of a portion of the installation containing the features constituting the present invention, section being 40 made in a vertical plane axial with respect to the temperature-responsive device, and as to the valve device at the plane indicated by the line 2—2 on Figure 3.

Figure 3 is a detail elevation at the plane indicated by the line 3—3 on Figure 2 looking in the direction of the arrow, 3X.

Figure 4 is a section at the line 4—4 on Figure 2.

Figure 5 is a section at the line 5—5 on Figure 3.

Figure 6 is a view of the character of a section at the line 6—6 on Figure 2 showing a modification.

Referring to the drawings in detail:

55. A represents a main valve of a dry pipe system

mounted on the water supply pipe, B, discharging through the main air pressure pipe, C, to a sprinkler pipe system indicated by the pipe, D, in the apartment to be protected, said discharge and main air pressure pipe line being connected for air pressure by an air pressure line, 15, leading from a source of compressed air indicated by the tank, M. E represents a vent pipe leading off from the main air pressure and discharge pipe, C, preferably as seen in Figure 1, in the protected 5 apartment proximately antecedent to the branching from said main discharge pipe of the pipes, D, constituting the sprinkler head system.

The pipe, E, leads to a fitting, F, at which it is connected at the inlet port, 20 (see Figure 5) of 15 a passage, 21, which passage turns for discharge at a port, 22, in a chamber formed by a hood, 24, preferably, as indicated, made of transparent material, as glass, to facilitate inspection without disassembly or opening which would vent the air 20 pressure. The port, 22, is controlled by a valve, 25, held firmly seated against the pressure by a displaceable strut, 26, preferably frangible, as hereinafter more particularly described. The bottom of the chamber, which is enclosed by the hood, 25, 24, has a plurality of outlet ports, 27, distributed around the port, 22, on three sides thereof, as seen in Figure 2, said ports leading to a discharge port, 29, at which there is connected a pipe, 30, which may lead to any convenient point for delivery of 30 the air which will be discharged through said pipe when the valve, 25,—hereinafter referred to as the vent valve,—is opened for venting the air pressure of the system.

The opening of the vent valve is to be controlled by some form of temperature-responsive device which shall operate for opening the valve when the temperature conditions in the apartment are such as result from fire danger. The valve being held shut by the strut, 26, will be 40 opened by the air pressure when the strut is broken; and for breaking the strut, which, as shown, may be understood to be made of glass or similar frangible material, there is provided a thrust pin, 31, mounted in a slightly flexible 45 diaphragm, 32, which closes a lateral opening in the hood, 24. Said thrust pin is directed laterally against the strut at about the middle point of the length of the latter, and being arranged for protruding from the hood is positioned to 50 be encountered by a weight, 35, carried by a lever, 36, which is mounted and controlled as to its movement for swinging the weight into encounter with the thrust pin.

The temperature-responsive element comprises 55

- a housing, H, substantially tubular, but open at the lower side for the greater part of its length as indicated at h, said housing being mounted in any convenient manner on the wall or ceiling 5 of the apartment, as by hangers or brackets, h¹, h¹. This housing carries metal rods, I and J, the rod, I, being of relatively large diameter, and the rod, J, being relatively slender. Both rods are made fast at one end in the head plates, 10 h², of the housing, which has mounted in it at the other end a bracket member, K, formed with a web, k, which constitutes the head plate of the housing at that end. The bracket, K, may constitute the support for the fitting, F, and may 15 be, as shown, integral with the latter; and it is extended for affording pivotal support, as seen at 31, for the weighted lever, 36, which extends upwardly from said pivot with the weight, 35, overhanging from the pivot.
- 20 Said weighted lever is held normally at that position against gravity by a latch member, 40, pivoted at one end to the web, k, of the bracket, K, which engages a catch, 42, carried by the lever, 36, all as seen in Figure 2.
- 25 The further detail construction of the temperature-responsive device and its connections for latching and releasing the weight may be understood from the drawings without further description.
- 30 It may be understood that the means of releasing the vent valve consisting in employing a frangible strut and breaking it to effect the release of the valve is not essential to the present invention, though for certain reasons a frangible strut may be preferred.
- 35 In Figure 6 there is illustrated a modification of the structure shown in Figures 2, 4 and 5, in which there is employed a construction consisting of a toggle comprising two link elements, 101 and 102, pivotally stepped at their proximate ends, the link, 101, being stepped at its opposite end on the valve, 100, and the link, 102, at its opposite end being stepped against the stop screw, 104, set through the end of a yoke member, 103, 40 which is formed integrally with the valve seat 45 spanning and overhanging the same.
- 40 The toggle strut, 101, has a short lever arm, 105, projecting from one side, and the toggle strut member, 102, has a similar lever arm, 106, projecting at the same side, and the two lever arms, 105 and 106 are connected by a two-part link whose two parts, 107 and 108 are soldered together, and adapted to become separated by 50 the fusing of the solder.
- 45 The link member, 107, is connected to the lever arm, 106, of the upper toggle strut member by the engagement of an aperture, 109, of the link with the reduced terminal of the lever arm, 106. The link member, 108, is engaged at its lower end 55 with a lever arm, 105, of the toggle link, 101, by an aperture in the lower end of said link member engaging a frangible pin, 110, which is held in a socket formed in the end of the lever arm, 105, said frangible pin projecting a substantial 60 distance outwardly from the link in position to receive the thrust of the thrust pin, 31, when the latter is encountered by the weight, 35, upon 65 the operation of the thermostat device, as above described.
- 70 Upon considering this construction it may be understood that the vent valve will be opened for venting the air pressure region of the system by the breaking of the frangible pin, 110, which 75 will release the fusible link without fusion of the latter, and thereby release the toggle strut mem-

bers which will fall out and release the vent valve. But if for any reason the temperature-responsive structure mounted as described in the upper part of the apartment fails to operate for releasing the weight, 35, promptly upon the occurrence of the temperature conditions which should cause it to thus operate, as for example, if the rise of temperature, though due to fire is very slow, although it eventually reaches the danger point, nevertheless when the temperature in the vicinity of the vent valve is sufficient to fuse the fusible link, the vent valve will be opened as promptly as the closed sprinkler heads in the apartment will be opened by the same cause and in the same manner, namely, by the fusing of the links by which they are held closed; and the advantage of venting the air pressure by way of the vent valve and its discharge connection leading to the exterior or to an open sprinkler head, and avoiding to a large extent the discharge of the air through 20 the sprinkler heads in the apartment, objectionably venting the fire when the sprinkler heads are opened by the fusion of their links.

I claim:

1. In a construction for the purpose indicated, 25 in combination, a valve chamber having an inlet port and an outlet port and fixed stop means opposite the inlet port; a valve within the chamber seating at the inlet port; a toggle strut wholly within the chamber having one toggle member 30 stepped on the valve and the other toggle member stopped on said stop means, said toggle members having each a lever arm, said arms both projecting transversely of the toggle members respectively at the same side of the toggle, one of 35 said arms having a terminal hook and the other arm having a frangible terminal pin; a link connecting the two lever arms by engaging at one end the hook and at the other end the frangible pin; and a thrust rod mounted in the chamber 40 wall protruding inwardly from its mounting into contact with said frangible pin laterally of the latter and protruding outside the chamber for exposure to means for thrusting it inwardly for breaking the frangible terminal.

2. In a construction for the purpose indicated, 45 in combination, a valve chamber having an inlet port and an outlet port and fixed stop means opposite the inlet port; a valve within the chamber seating at the inlet port; a toggle strut wholly 50 within the chamber having one toggle member stepped on the valve and the other toggle member stopped on said stop means, said toggle members having each a lever arm, said arms both projecting transversely of the toggle members respectively at the same side of the toggle, one 55 of said arms having a terminal hook and the other arm having a frangible terminal pin; a fusible link connecting the two lever arms by engaging at one end the hook and at the other end the frangible pin; and a thrust rod mounted in the chamber wall protruding inwardly from its mounting into contact with said frangible pin laterally of the latter and protruding outside the 60 chamber for exposure to means for thrusting it 65 inwardly for breaking the frangible terminal.

3. A device for protection against fire consisting of a fitting adapted to be interposed in a fluid flow pipe line for controlling fluid pressure flow therethrough, said fitting comprising two 70 members detachably mounted one upon the other, the first member having an inflow and an outflow passage arranged for connection respectively with the pressure flow source and destination, said passages being partitioned from each 75

other in said first member and having each an outlead from said member at one side thereof, the second member having a single unpartitioned cavity open at one end, said second member being mounted with sealed junction on the first member with the open end of said second member embracing both said outleads of the first member flow passages; a valve mounted in the second member seating at the outlead from the source-connected passage; a strut in the second member for holding said valve seated; means mounted in the second member movable in relation to the operative position of the strut for causing displacement of the latter to release the valve, said means having exteriorly exposed connection for deriving said strut-displacing movement.

4. A device for protection against fire consisting of a fitting adapted to be interposed in a fluid flow pipe line for controlling fluid pressure flow therethrough, said fitting comprising two members detachably mounted one upon the other, the first member having an inflow and an outflow passage arranged for connection respectively with the pressure flow source and destination, said passages being partitioned from each other in said first member and having each an outlead from said member at one side thereof, the second member having a single unpartitioned cavity open at one end, said second member being mounted with sealed junction on the first member with the open end of said second member embracing both said outleads of the first member flow passages; a valve mounted in the

second member seating at the outlead from the source-connected passage; a strut in the second member for holding said valve seated comprising a fusible part wholly within the chamber by whose fusion the strut is dismembered and releases the valve, and means mounted in the second member movable in relation to the operative position of the strut for causing displacement of the latter to release the valve, said means having exteriorly exposed connection for deriving said strut-displacing movement.

5. A device for protection against fire consisting of a fitting adapted to be interposed in a fluid flow pipe line leading from a selected location in the protected apartment, for controlling fluid pressure flow therethrough, said fitting comprising a valve chamber and a valve seated therein, a strut device controlling said valve holding it normally seated against the fluid flow, said strut device having parts displaceable for releasing the valve and arranged to yield to flow pressure tending to open the valve for said displacing movement, the strut device including fusible means arranged to hold the displaceable strut parts in undisplaced relation to the valve and to release said displaceable parts for releasing the valve upon fusion of said fusible elements, said strut parts including said fusible element being completely enclosed in the valve chamber, said chamber comprising two separable members by whose separation access is afforded to the valve chamber and the strut parts therein.

EMIL TYDEN.
